UNITED STATES PATENT OFFICE.

JOEL STARRELS, OF NEW YORK, N. Y.

PROCESS FOR PRODUCING FATTY ACIDS OF HIGH PURITY AND MELTING-POINT.

1,209,512.

Specification of Letters Patent. Patented Dec. 19, 1916.

No Drawing.

Application filed March 1, 1916. Serial No. 81,336.

To all whom it may concern:

Be it known that I, JOEL STARRELS, a citizen of the United States, and a resident of New York, in the county of New York and State of New York, have invented certain new and useful Improvements in Processes for Producing Fatty Acids of High Purity and Melting-Point, of which the following is a specification.

This invention relates to a method of producing fatty acids of high purity suitable for the manufacture of candles and high grade toilet soaps and for similar purposes and relates particularly to a product prepared from hydrogenated fatty oil.

When a fatty oil such as corn, cottonseed or cocoanut oil and the like is subjected to the action of hydrogen in the presence of a catalyzer such as finely-divided nickel, certain bodies of a hydrocarbon nature are formed, presumably by the catalytic reduction of the acid or carboxyl group and these hydrocarbons especially the partially saturated ones seemingly tend to discolor at the temperature of the hydrogenation process forming dyestuffs or coloring agents of a brown or black character which seriously impair the quality of the fatty material from the soap maker's standpoint.

It is the object of the present invention to produce free fatty acids and particularly stearic acid or equivalent fatty material from a fatty oil, which fatty acids are substantially free from these deleterious unsaponifiable hydrocarbons and discoloring agents and which are capable of forming a perfectly saponified soap of a fine texture and grain such as could not be advantageously obtained in the presence of the unsaponifiable agents and coloring compounds aforesaid.

The hydrogenating treatment is not a part of my invention and no claim is laid to this treatment of the oil.

For this purpose I preferably harden a fatty oil to a high melting point, as for example, to about 60° or 62° C. and an iodin number of from zero to 2 and thereby substantially completely converting the olein into stearin, also forming various isomers of high melting point. At the same time the objectionable constituents referred to are formed in greater or less degree, thereby contaminating the product and rendering it comparatively low grade. The material is then saponified by the Twitchell process or

any of the other fat splitting processes yielding glycerin and high melting point fatty acids. The latter is then exposed to the action of a solvent medium, as for example, 60 alcohol or gasoline, preferably in an amount not exceeding an equal weight or thereabout, preferably being heated with the solvent so as to dissolve therein until a substantially homogeneous liquid is obtained when the 65 material is carefully cooled and the free fatty acids are separated in a state of purity leaving in solution the greater part of the hydrocarbons and occluded coloring agents.

An example, illustrative of the present invention is the following:—Corn oil was hydrogenated using a nickel catalyzer until the melting point was about 62° C., it was then subjected to the Twitchell process and the fatty acids obtained. These are brown in 70 color. Approximately equal parts of denatured alcohol and the fatty acid were incorporated and heated to form a homogeneous solution which takes place rather readily at temperatures approaching the boiling point 80 of alcohol as the fatty acid is relatively soluble in alcohol, while glycerids are highly insoluble. The solution was again cooled until practically all of the fatty acid had separated, when the material was pressed and a 85 brown extract containing the hydrocarbons and dyestuffs was removed leaving a white fatty acid of very high saponification value and acid number showing that the unsaponifiable material formed by the stage of 90 hydrogenation had been eliminated.

Proceeding along similar lines the fatty acids of cottonseed, fish, whale and other vegetable or animal oils may be treated to form high grade fatty acids suitable for the 95 manufacture of first class toilet soaps.

In order to produce fatty acids of desirable quality practically free from olein and other liquid or soft fatty acid it is necessary to force the hydrogenation step to the 100 utmost in order to reduce the iodin number practically to zero, and such forced operation tends to aggravate the formation of unsaponifiable material such as hydrocarbons leading to the subsequent difficulties in saponification of such material in the ordinary course in the manufacture of soap unless the method of eliminating hydrocarbons illustratively described herein be employed.

In the manufacture of high grade stearic acids by the process heretofore practised it

is customary to twitchellize or saponify by any one of the processes in vogue a relatively soft fat containing such a quantity of oleic acid that the material could be seeded 5 and pressed to yield fairly good quality stearic acid. By the present process it is unnecessary to go to the great expense of installing and operating the seeding pans and presses as the hardening operation enables the stearic acid to be produced of high 10 melting point while the selective removal of hydrocarbon material and dyestuffs enables this material to be converted into merchantable fatty acids of the desired grade. The 15 fatty acids produced by this process are white in color and well adapted for the manufacture of candles.

What I claim is:—

1. The process of making white fatty 20 acids suitable for the manufacture of high grade toilet soaps which comprises hardening a liquid oil, separating the fatty acid by twitchellizing and subjecting such fatty acid to the action of solvent material capable of removing the unsaponifiable matter formed during the hardening operation.

2. The process of making fatty acids suitable for the manufacture of high grade 30 toilet soaps which comprises subjecting a liquid fatty glycerid to the action of hydrogen in the presence of nickel whereby the liquid glycerid is converted into a solid glycerid, in forcing the hydrogenation to almost completely reduce the iodin number 35 to zero; whereby hydrocarbon bodies and coloring matters are formed, in subjecting the resulting hard glycerid to a fat splitting process whereby the glycerin is separated from the fatty acids and in eliminating the 40 hydrocarbons and coloring matter formed by the hydrogenation stage whereby pure fatty acids of high melting point are obtained.

3. The process of making stearic acid, 45 light in color, suitable for the manufacture of candles, which comprises subjecting a liquid fatty glycerid to the action of hydrogen in the presence of nickel whereby the

liquid glycerid is converted into a solid glycerid, in forcing the hydrogenation to 50 almost completely reduce the iodin number to zero whereby hydrocarbon bodies and coloring matters are formed, in subjecting the thus obtained fatty glycerid to a fat splitting process whereby the glycerin is 55 separated from the fatty acids, and in eliminating the hydrocarbons and coloring matters formed by the hydrogenation stage whereby pure fatty acids of high melting point and good color are obtained. 60

4. The process of making stearic acid suitable for the manufacture of candles or high grade toilet soaps which comprises subjecting an unsaturated solid fat or semi-solid fat such as tallow or grease to 65 the action of hydrogen in the presence of finely divided nickel whereby the unsaturated fat is saturated with hydrogen, thereby reducing its iodin number to zero, or very near it, and raising its melting point to 70 around 62° C. or thereabout, whereby hydrocarbon bodies and coloring matters are produced, and in subjecting the fatty glycerid thus obtained to a fat splitting process, thereby separating the glycerin from the 75 fatty acids and in removing the coloring matter formed by the hydrogenation stage whereby pure fatty acids of high melting point and good color are obtained.

5. The process of making fatty acids 80 adapted for use in the manufacture of high grade toilet soaps, candles and the like, which comprises hydrogenating a fatty oil containing unsaturated material, separating the fatty acid by twitchellizing, subjecting 85 such fatty acid to the action of volatile solvent material capable of dissolving impurities and in removing the solvent material with such impurities.

Signed at New York, in the county of 90 New York and State of New York, this 26th day of February, A. D. 1916.

JOEL STARRELS.
